DESIGN FOR A SHOE OR A SIMILAR ARTICLE

Wallace Bradley Mackey, Upper Montclair, N. J.

Application September 30, 1936, Serial No. 65,069

Term of patent 7 years

To all whom it may concern:

Be it known that I, Wallace Bradley Mackey, a citizen of the United States, residing at 75 Oakwood Avenue, Upper Montclair, in the county of Essex and State of New Jersey, have invented a new, original, and ornamental Design for a Shoe or Similar Article, of which the following is a specification, reference being had to the accompanying drawing, forming part thereof.

Fig. 1 is a front perspective view of a shoe showing my new design; and

I claim:

The ornamental design for a shoe or a similar article, as shown.

WALLACE BRADLEY MACKEY.
